UNITED STATES PATENT OFFICE.

ALDEN L. PUTNAM, OF DETROIT, MICHIGAN, ASSIGNOR, BY MESNE ASSIGNMENTS, OF ONE-HALF TO MOTOR WHEEL CORPORATION, OF LANSING, MICHIGAN, A CORPORATION OF MICHIGAN, AND ONE-HALF TO THE MIDLAND STEEL PRODUCTS COMPANY, OF CLEVELAND, OHIO, A CORPORATION OF OHIO.

VEHICLE WHEEL.

Application filed March 24, 1919. Serial No. 284,715.

To all whom it may concern:

Be it known that I, ALDEN L. PUTNAM, a citizen of the United States of America, residing at Detroit, in the county of Wayne 5 and State of Michigan, have invented certain new and useful Improvements in Vehicle Wheels, of which the following is a specification, reference being had therein to the accompanying drawings.

10 The invention relates to vehicle wheels of the dished disk type and it is the primary object of the invention to obtain a demountable construction which is reversible.

In the present state of the art dished disk 15 wheels have been devised in which the dish of the disk crosses the central plane of the wheel or plane of impact, the inner portion being secured to the hub and the outer portion to the rim on opposite sides of said 20 central plane. The advantage of such construction is the added strength which is obtained, but by reason of the fact that the point of attachment to the hub is on one side of the central plane of the wheel, the 25 disk cannot be reversed without alteration in location of the tread. On the other hand, where the dishing of the disk is such as to bring the point of attachment to the hub in the central plane thereof, the construction 30 is reversible but is not as strong.

To obtain the combined advantage of crossing the plane of impact and of reversibility, I have devised a construction in 35 which the disk is dished from opposite sides thereof, the outer portion crossing the central plane of impact and the inner portion returning to said central plane. With such a construction the wheel may be reversed without altering the location of the tread, 40 while the strength and resiliency is even greater than where dished on one side only.

In the drawings:

Figure 1 is a section through the wheel;

45 Figure 2 is a similar view showing the wheel in reversed position;

Figure 3 is a side elevation.

A is the hub of the wheel, which may be of any suitable construction, having an outwardly extending annular flange B. As 50 specifically shown, this flange is located upon the inner side of the central plane of the wheel and has the brake drum C directly bearing thereagainst, and a ring D on the

outer side of the brake drum which forms a seat for the disk in the central plane of the wheel. E are studs having shoulder portions E' for bearing against the ring D and clamping the same, together with the brake drum C, to the flange B. These studs have outwardly projecting threaded portions G for securing the disk through the medium of the outer clamping ring H and securing nuts I or other equivalent means.

55 My improved disk wheel comprises a center portion J which is preferably parallel to the plane of the wheel and is adapted to seat against the ring D and to be clamped thereto by the ring H. The inner end of this central portion is preferably provided with a turned flange K which bears upon a cylindrical portion of the hub A and alternately engages recesses L and M in the rings H and D according to which way the disk 60 is turned. Surrounding the central portion J is a dished portion N extending upon one 65 side of the central plane of the wheel, and surrounding this portion is an oppositely dished portion O which crosses the central plane of the wheel and at its periphery is secured to the rim P by any suitable means, 70 such as the clamping bolts Q engaging aligned apertures in the disk and inwardly extending flanges R and R' of complementary rim sections. The disk is also preferably of a tapering cross-section, gradually 75 diminishing from the gauge of the central portion J to that of the peripheral portion.

80 With the construction as described, when the disk is mounted upon the hub, as shown in Figure 1, the portion N extends inwardly and the portion O outwardly, giving a general concave form to the outer side. This arrangement is preferred for certain uses 85 both on account of the appearance, which is pleasing, and for other mechanical reasons. On the other hand, with this arrangement of the wheel the tire inflation tube 90 will be arranged on the inner side of the disk; and where the clearance between the brake drum and the rim is small it is difficult to find access to the tube when the tires are to be inflated. However, by reversing the disk, as shown in Figure 2, the inflation tube will be exposed as indicated in dotted lines at S, which will avoid all difficulty. 95

100 In addition to the advantages above de-

scribed, my improved construction of wheel has greater strength and resiliency than a single dished disk, while the appearance is also improved.

5. What I claim as my invention is:

1. In a vehicle wheel, the combination with a hub and rim, of a disk connecting said hub and rim having two reversely dished portions, and an undished portion 10 outside the dished portion and substantially horizontal rim-securing bolts passing through said undished portion.

2. In a vehicle wheel, the combination with a hub and a rim, of a disk having its 15 main portion dished inwardly from the rim to one side of the central plane of the wheel, an oppositely dished portion of relatively small area adjacent the hub, and a securing portion substantially in the plane of impact. 20

3. In a vehicle wheel, the combination with a hub having a cylindrical portion and an outwardly extending portion adjacent to the central plane of the wheel, a rim, and a 25 disk extending between said hub and rim having a central portion seated on the outwardly extending portion of the hub, a dished portion extending from said central portion to one side of the central plane, and 30 an oppositely dished portion extending from first mentioned dished portion crossing the central plane and secured to the rim on the opposite side thereof.

4. In a vehicle wheel, the combination 35 with a hub and a rim, of a disk extending between said hub and rim having a portion

adjacent to the hub in the central plane of the wheel and provided at its inner edge with a turned flange for bearing on the cylindrical portion of the hub, a portion outside of said central portion dished to extend on one side of the central plane of the wheel, a portion outside of said dished portion oppositely dished and crossing the central plane of the wheel, being secured to said rim on the opposite side of said plane, and clamping bearings for said disk on opposite sides thereof, said bearings being cut away to receive the turned flange of the disk when turned with either face outward. 40 45

5. In a vehicle wheel, the combination with a hub and a rim, of a disk connecting said hub and rim, having a gradually dished outer portion and an oppositely dished inner portion of abrupt inclination, and of relatively small area as compared to said outer portion. 50

6. In a vehicle wheel, the combination with a hub and a rim, of a disk connecting said hub and rim, having an abruptly dished inner portion and an oppositely dished outer portion of gradual inclination. 60

7. In a vehicle wheel, the combination with a hub and a rim, of a disk having an inner portion substantially in the plane of impact, an adjacent abruptly dished portion, and a gradually dished body portion crossing the plane of impact, and securing means engaging said inner portion. 65

In testimony whereof I affix my signature.

ALDEN L. PUTNAM.
